UNITED STATES PATENT OFFICE.

ALDEN L. PUTNAM, OF DETROIT, MICHIGAN, ASSIGNOR TO DETROIT PRESSED STEEL COMPANY, OF DETROIT, MICHIGAN, A CORPORATION OF MICHIGAN.

VEHICLE-FRAME.

1,181,346.

Specification of Letters Patent.

Patented May 2, 1916.

Application filed January 19, 1915. Serial No. 3,085.

To all whom it may concern:

Be it known that I, ALDEN L. PUTNAM, a citizen of the United States of America, residing at Detroit, in the county of Wayne 5 and State of Michigan, have invented certain new and useful Improvements in Vehicle-Frames, of which the following is a specification, reference being had therein to the accompanying drawings.

10 The invention relates to vehicle frames, and more particularly to the construction of the side sills and spring hangers thereof.

It is the object of the invention to obtain a construction formed solely from sheet 15 metal and which is simple and inexpensive to manufacture.

In the drawings: Figure 1 is a plan view of the end portion of my improved frame; Fig. 2 is a side elevation thereof; Fig. 3 is a 20 cross section on line $x-x$ Fig. 1; and Fig. 4 is a perspective view thereof.

In the present state of the art it is usual to form the side sills of automobiles of pressed sheet metal channel beams opening 25 inwardly. The ends of the sills are also provided with horns or hangers for attachment to the spring suspension. To form a structure completely of sheet metal and from a single blank would require complex 30 die operations and would also require a blank of a form which would involve considerable waste in cutting. Furthermore, as the gage of the sheet metal is uniform the reduced portion adjacent to the hanger 35 would be deficient in strength; and still another difficulty is in forming the bifurcated hanger having parallel sides from the same blank in which the channel portion is open upon the inner side.

40 With my improved construction I avoid these difficulties by forming the sill and hanger of separate sheet metal blanks, which are secured to each other in such a manner as to increase the strength of the structure. 45 These blanks can be cut from metal with less waste than a single blank, and the die operations for pressing them are also simpler than required where pressed from a single blank.

50 In detail, A is the sill which is of the usual channel form having top and bottom flanges B and B' extending inward from the connecting vertical web C. This sill terminates at a point adjacent to the 55 hanger and the latter is formed from a sepa-

rate blank, also of channel section but turned with its open side at the bottom. This permits of readily forming the parallel sides D and D' for receiving the pivot pin of the suspension, also the top web E curved 60 downward at the end to form a hood, while extending from this portion is a shank portion F for fitting in the channel of the sill. The shank portion F is preferably of channel shape at the point of entrance in the 65 end of the sill, and is then cut away to form an angle-section having the adjacent sides G and G'. The side G extends in a vertical plane adjacent to the vertical web of the sill, to which it may be secured by riveting 70 or other suitable means. The side G' extends adjacent to the top flange of the sill and is tapered toward its inner end so as to avoid any abrupt change which might form a line of weakness. 75

When the sill and hanger are secured together the tapering shank of the latter forms a reinforcement for the joint, so that the structure is of greater strength than possible where made of a single blank. Both 80 the sill and the hanger are comparatively simple in structure and can be made by simple die operations, while the opening of the channel at the bottom in the hanger portion and at the side in the sill portion is readily 85 obtained.

If desired, the sill A may be provided at its end with inturned flanges H and H', welded or otherwise secured to each other, so as to form a close loop surrounding the 90 shank of the hanger.

What I claim as my invention is:—

1. In a vehicle frame, the combination with a pressed sheet metal sill having a laterally-opening channel-section, of a hanger 95 at the end of said sill having a downwardly-opening channel forming parallel sides, and a hooded top, said hanger being provided with a shank extending into the channel of said sill and said shank having a vertical 100 web secured to the vertical web of the sill, and a lateral flange adjacent to the lateral flange of the sill, tapering toward its inner end.

2. In a vehicle frame, the combination 105 with a pressed sheet metal sill having a laterally-opening channel section, of a hanger formed of a separate blank, provided with a downwardly-opening channel section forming parallel sides and a hooded top, and a 110

- shank extending inwardly into the channel of said sill and changing from a channel to an angle section with a tapering lateral flange.
- 5 3. A vehicle frame, comprising a pressed sheet metal sill having a laterally-opening channel section, a hanger at the end of said sill formed from a separate pressed sheet metal blank having a downwardly-opening channel section forming parallel sides and a hooded top, a shank extending inward from said hanger of channel section, changing to angle section, said angle section having a tapering laterally-extending flange,
- 10 15 and a vertical web adjacent to the vertical web of the sill and secured thereto.
4. In a vehicle frame, the combination with a pressed sheet metal sill having a laterally-opening channel-section, of a pressed sheet metal hanger formed from a separate blank and provided with a downwardly-opening channel-portion and a shank extending within said sill, and inturned flanges upon the flanges of said sill integrated with each other to form a closed loop surrounding the shank of the hanger.

In testimony whereof I affix my signature in presence of two witnesses.

ALDEN L. PUTNAM.
